[57] **CLAIM**

The ornamental design for a knob for guitar head, as shown and described.

DESCRIPTION

FIG. 1 is a top view of knob for a guitar peg head showing my new design;

FIG. 2 is a front view thereof;

FIG. 3 is a rear view thereof;

FIG. 4 is a left side view thereof;

FIG. 5 is a right side view thereof;

FIG. 6 is a cross sectional view thereof on the line 6—6 in FIG. 1; and,

FIG. 7 is a top front perspective view thereof.

The bottom view is omitted as the bottom is plain and unornamented.
